UNITED STATES PATENT OFFICE

138,367

DESIGN FOR A TOY

Christos M. Katsetos, Cincinnati, Ohio

Application April 20, 1944, Serial No. 113,312

Term of patent 3½ years

(Cl. D34—15)

To all whom it may concern:

Be it known that I, Christos M. Katsetos, a citizen of the United States of America, residing at Cincinnati, in the county of Hamilton, State of Ohio, have invented a new, original, and ornamental Design for a Toy, of which the following is a specification, reference being had to the accompanying drawing, forming part thereof.

The figure is a perspective view of the toy, showing my new design.

I claim:

The ornamental design for a toy, as shown.

CHRISTOS M. KATSETOS.
